UNITED STATES PATENT OFFICE

JOSEPH DE LA MAR, OF NEW YORK, N. Y.

PROPELLER-WHEEL.

No. 847,961.

Specification of Letters Patent.

Patented March 19, 1907.

Application filed June 18, 1906. Serial No. 322,168.

To all whom it may concern:

Be it known that I, JOSEPH DE LA MAR, a citizen of the United States, residing at New York, in the county of New York and State 5 of New York, have invented certain new and useful Improvements in Propeller-Wheels, of which the following is a specification.

My invention pertains to propeller-wheels and it has particular reference to what is 10 known as "spiral" propellers, in which a plurality of blades is disposed along the shaft. My object is to provide a propeller which, in its rotary motion will offer as little resistance as possible at the core of the wheel, 15 and to this end I have devised a spirally-formed rib, the opposite ends of which are rigidly secured to the shaft, and which has thereon removable blades within and without the rib whereby an effective action is produced by the same, as will now be set forth in detail.

In the drawings, Figure 1 is a side elevation of my improved form of propeller-wheel, and Fig. 2 is a rear end view of the same.

In constructing my invention I provide a 25 propeller-shaft 3, on which I place two fixed collars 4 5, to the forward collar 4 of which I attach one end of a spirally-formed rib 6 and to the rear collar is attached the rear end of 30 the rib. This attachment may be made by means of screws 7 or otherwise, and these collars are keyed (not shown) or otherwise rigidly secured to the shaft. Externally on 35 this rib and at suitable intervals I place blades 8. These may be secured by bolts 9 through the rib or in any other preferred manner, each blade having a projecting boss 10 on one side, through which the bolt passes, and it is obvious that this method of 40 attaching the blades permits me to dispose of them at any suitable angle or pitch.

In practice the spiral is so formed that it turns, as indicated at the darts 11, in the direction of the coil, so that the only resistance 45 to the body of water around the shaft is that caused by the collars to which the ends of the ribs are attached.

Interiorly blades 12 are placed on the rib 50 equal in number to the exterior blades, or a greater or less number, as may be considered most effective, and these may be located without reference to the location of the outer blades. In this case, however, I show the interior blades attached by the same bolts as 55 are employed to secure the outer blades and

they are also disposed at the same pitch. In practice the inner blades should have a greater pitch than the outer blades, as will be obvious to the engineer.

By reference to Letters Patent No. 823,476, 60 issued to me on the 12th day of June, 1906, it will be seen that the spirally-formed rib has one of its ends secured to a tubular shaft and its other end to an inner shaft and that the exterior blades are attached to the rib, while 65 the interior blades are attached to the inner shaft and the two sets of blades revolve in the opposite direction. Such construction, however, necessitates gearing which I dispense with in the present invention. In the 70 present invention it will be obvious that I have simplified the construction, inasmuch as I attach both ends of the spiral rib to a single shaft and have both the inner and the outer blades attached to a rib, which therefore 75 frees the shaft of any collars or other necessary obstructions necessary to attach blades thereto and greatly cheapens the construction.

What I claim as new is—

1. A propeller-wheel, comprising a shaft having thereon a spirally-formed rib, both ends of which are rigidly secured thereto, and having blades thereon.
2. A propeller-wheel, comprising a shaft 85 having thereon a spirally-formed rib, both ends of which are rigidly secured thereto, and having a plurality of exterior blades thereon.
3. A propeller-wheel, comprising a shaft 90 having thereon a spirally-formed rib, both ends of which are rigidly secured thereto, and having a plurality of interior blades thereon.
4. A propeller-wheel, comprising a shaft 95 having thereon a spirally-formed rib, both ends of which are rigidly secured thereto, and having a plurality of exterior and interior blades.
5. A propeller-wheel, comprising a shaft having thereon a spirally-formed rib, both ends of which are rigidly secured thereto, and having blades thereon adapted to be adjusted at any desired pitch.

6. A propeller-wheel, comprising a shaft 100 having thereon a spirally-formed rib, with its opposite ends rigidly secured thereto, having exterior blades and interior blades attached thereto, one set of blades being adapted to be adjusted at a different pitch from the other set.

7. A propeller-wheel, comprising a shaft 11.

having thereon, and rigidly secured thereto, the ends of a spirally-formed rib, a plurality of blades projecting outwardly from said rib, and a plurality of blades projecting inwardly from said rib, and attached thereto.

8. A propeller-wheel, comprising a shaft having thereon, and rigidly secured thereto, the ends of a spirally-formed rib, a plurality of inner and outer blades secured to said rib,

10
said inner and outer blades being disposed in the same general direction to the rib.

Signed at New York, in the county of New York and State of New York, this 12th day of June, A. D. 1906.

JOSEPH DE LA MAR.
